LOOM SHUTTLE

James T. Curboy, Southbridge, Mass., assignor
to Albert E. Leon, Belmont, Mass.

Application May 25, 1934, Serial No. 727,458

3 Claims. (Cl. 139—223)

This invention relates to loom shuttles and more particularly to the self-threading construction of loom shuttles that are used in automatic looms.

Practically all threading devices that are commercially practicable are made of cast metal with one or more parts or members overhanging underneath parts, so as to retain or confine the yarn passing from the bobbin to the shuttle delivery eye against unthreading, while facilitating the operation of self-threading. Now inasmuch as it was not practicable to cast threader blocks with the overhead or overhanging threading members overlying other parts of the shuttle, it was the practice to make the threader block castings of relatively soft alloys of brass or bronze, which could be cast in open or distorted form and then bent under pressure to give the desired overhanging relationship of parts, or it was necessary to make the threader with the overhanging member inserted as a separate piece.

It is of course essential that the threader should have a form of construction that would reliably insure the automatic threading of the shuttle and that would prevent the unthreading of the yarn from the shuttle, or the looping of the yarn around some part of the shuttle threader so as to produce a breakage of the yarn.

It is the object of the present invention to produce an efficient and thoroughly reliable threader construction that can be readily made from a single or one-piece casting which needs no bending or distortion from its original cast form to fit it for efficient and reliable service. As a consequence of this construction, it is possible to make an exceedingly efficient and dependable threader of cast iron or other unbendable metal in one piece, although it will be understood that the invention is applicable to other material beside cast iron.

In the accompanying drawing is illustrated a novel construction of threader embodying the principles of this invention, in which

Fig. 1 is a plan view showing the forepart of the shuttle with the threader block mounted in a suitable recess formed therein for its reception.

Fig. 2 is a side elevation of the parts shown in Fig. 1.

Fig. 3 is a rear end elevation of the threader showing the longitudinal cylindrical bore at the rear end thereof and the inlet slot communicating with one side of said bore.

Fig. 4 is a view showing the one-piece casting before it is machined to form the threader.

Fig. 5 is an elevation showing the complete

threader block illustrated in the previous figures as viewed from the side opposite the thread eye of the shuttle.

Fig. 6 is a rear end view of a threader block embodying the same principle for a reverse wound bobbin.

Fig. 7 is a perspective view showing the threader and the thread eye somewhat separated to show the course of the yarn through the thread block and delivery eye.

Fig. 8 is a perspective view from the outside showing the improved delivery eye.

As shown in Fig. 1 the forepart of the shuttle body A is suitably recessed or cut away, as shown at A', A'', forwardly of the bobbin chamber B for the reception of the threader block or casting containing the present improvements. On the left side of the shuttle forepart (as the shuttle is viewed from the front end) is provided a lateral outlet opening or passage in which is shown inserted a novel form of delivery eye, presently to be described, and forming part of the present improvements.

The threader casting or block, cast in a single piece substantially in the form shown in Fig. 4, 25 may, for purposes of description, be regarded as comprising an oblong base portion or member 1, preferably of approximately rectangular form, and superposed on or carried by the rearward portion of moiety of this base is an approximately 30 quadrant shaped member 2, whose curved or convex, approximately arcuate surface at 2' extends from its high point at one side of the block across and down to the top of the opposite side of the base for the purpose of providing an arched roof 35 or bridge member above the base and overhanging the rearward portion of the base. The lower edge of this bridge member at 2' terminates slightly inside the adjacent side face of the base and is preferably inclined slightly forwardly and inwardly 40 in relation to that side of the base.

Somewhat in advance of the lower side of the bridge member 2 and spaced therefrom is an upstanding or upright guide member 3. On the delivery side of the threader, that is, the side nearest the shuttle delivery eye, there is formed an elevated yarn-guiding beak 4 of approximately triangular form, as shown, whose top face is convexly curved and which has its inner edge 5 and its outer edge 6, as viewed in plan, converging to a 50 downwardly projecting tip 7 lying in a vertical plane.

On the underside of the beak and forming a substantially vertical connecting web 9 for the beak is a yarn-guiding and retaining horn 8, 55

whose forward edge 8^a is inclined downwardly and rearwardly to guide the yarn into an underneath yarn-retaining notch 8^b that is substantially in alignment with the delivery eye transversely of the shuttle.

Since the body of the yarn-guiding beak is supported a substantial distance above the level of the base 1 by the connecting and supporting vertical web 9, said web forms a side wall along one side of the open trough or recess 10 formed in the casting, which open trough is bounded on the other side by the upright guide member 3. The foregoing description of the threader block applies to the casting in its unfinished form. To fit the casting for the reception and retention of the yarn the bridge or quadrant shaped member is bored longitudinally and medially of the block, preferably with a slight upward and forward inclination corresponding to the inclination given 20 to the base at the open side of the block, as shown in Fig. 5.

The longitudinal medial bore 11 may have its rear end countersunk or flared slightly to accommodate ballooning yarn. The rear face of the bridge member is forwardly curved as shown at 25 12 to present a round corner for the entrance of the yarn. To provide an inlet passage for the yarn, I cut with any suitable cutter, such as a small thin milling tool, a longitudinal slot 13 severing the lower portion of the bridge from the upper surface of the base so that the lower edge of the bridge overhangs the underneath face of the base but is separated therefrom by a narrow longitudinal slot into which the yarn is guided in 30 the threading operation by engagement with the forwardly disposed upright guide 3, which tends to guide the yarn inwardly in conjunction with the whirling motion of the yarn caused by its ballooning when unwinding. The slot is longer 35 than the bore diameter.

It will therefore be seen that the rear portion of the block is provided with a longitudinal cylindrical bore forming the rear part of a medial thread passage, whose front part is formed by the open 40 trough between the two upright members 3 and 9. Since this passage is slightly upwardly inclined, the thread issues from its forward end somewhat above the level of the notch 8^b at the bottom of the horn. Of course the parts are 45 smoothly finished by any suitable buffing or polishing operation to provide smooth surfaces for contact with the yarn and if made of cast iron the metal may be subjected to any well known rust proofing treatment to avoid rust or corrosion. 50 The base member is provided with the customary transverse bolt orifice, as shown at 14, for anchoring it in place.

The form of threader above described is one that is intended for use on a normally wound 55 bobbin in which the yarn is coiled on the bobbin in a counterclockwise direction, as viewed from the forward end of the bobbin. However, the same principle is applicable to a bobbin having the so-called reverse wind and that form of 60 threader is shown in Fig. 6. In this form the bridge member 15 curves downwardly to the delivery side of the block from the opposite side so as to bridge over the rear and the lateral inlet slot 16 is cut through the delivery side of the 65 rear portion of the block into the medial cylindrical bore. In this case the web 17, which supports the forward guiding beak 4, forms the guide that is inwardly offset from the edge 15^a of the bridge to assist in threading the yarn into the medial 70 thread passage just as the inwardly offset guide 3

in the first-described form functions to assist the threading operation and also to prevent the unthreading.

The longitudinal dimension or length of the bridge member along the inlet slot serves as a 5 very reliable means of preventing the unthreading of the yarn in the case of a loop in the yarn being overcast by the sudden arrest of the shuttle movement in the shuttle blocks at its forward end and prevents all possibility of such loops being caught around the bridge member. The convex rear end of the bridge member serves to facilitate the guiding of the yarn into the bore, since there is no obstruction to the free entrance of the yarn into the rear end of the cylindrical 15 bore, while the forward guide member 3 serves to direct the yarn inwardly in aid of the threading operation. The rear end of the threader receiving recess A may be made somewhat narrower than the width of the threader block to form a 20 throat for limiting the lateral movement of the yarn, while also forming positioning and supporting ledges at the rear of the thread block, as shown at 19.

Since all parts of the threader block are cast 25 in one piece, it is not possible for any part to work loose or get out of the precise position which is necessary for efficient and reliable operation and since no bending or distortion of any part 30 of the casting is necessary to give it the proper form and relationship of parts, it is perfectly feasible to make a one-piece cast metal threader of harder and more rigid material than was possible under previous methods of manufacture, while producing a threader that is superior in respect to ease and certainty of threading and at 35 the same time wholly free from tieing or catching on the threader and from troubles due to unthreading when the yarn loops are overcast.

To eliminate unthreading of the yarn from the 40 delivery eye of the shuttle, I provide a novel construction of delivery eye, as illustrated in Fig. 1 and Fig. 7 and Fig. 8. This eye may be made of a piece of sheet metal or other suitable material, which is formed into an approximately U-shaped 45 loop comprising the forward member or leg 20 and a rear leg 21, which are preferably nearer together at their upper ends than at the closed bottom, so as to provide an entrance narrower than the body portion of the eye. The forward member 50 20 is provided with a yarn guiding and retaining finger or spur 22 bent rearwardly to overlap the rear member 21 and lying in a plane outwardly offset from said rear member to leave a 55 space for the yarn to pass into the eye. The spur 22 has its upper edge downwardly and rearwardly inclined to guide the yarn into the eye and has its underneath edge concave to guide the yarn over the intake and prevent its escape from the eye. The width of the eye transversely of the 60 shuttle is dimensioned so that when the eye is inserted with the inside edge of member 21 abutting against the side face of the threader block the whole eye lies somewhat inside the adjacent outside surface of the wooden shuttle body. The 65 inner edge of the forward member 20 is downwardly and inwardly curved to guide the yarn easily into the eye. The wood slightly overhangs the upper end of the forward member 20 to avoid the catching of the yarn in any open crack that 70 might be formed at that point.

What I claim is:

1. A one-piece shuttle threader of rigid cast metal whose rearward half has an upward extension of substantially quadrantal contour trans- 75

- versely of the base forming a downwardly curved bridge, whose rear end is convexly rounded, arching across a medial longitudinal cylindrical bore and separated along its lower side from the underneath marginal portion of the base to provide an elongated entrance slot below the transverse diametrical plane of the bore between top and bottom substantially parallel edges in a lengthwise direction of the threader for a substantially greater distance than the diameter of said bore, the forward portion of said base being formed with a trough-like passage open at its top and forming a continuation of said laterally slotted cylindrical bore, said passage being bounded on one side by an upstanding yarn guiding lug located at the forward end of the base and in forward alignment with, but well spaced from, the forward end of said slot, and an elevated yarn guiding beak bounding the opposite side of said passage and having a convexly curved top converging forwardly to a vertically depending tip located in axial alignment with said bored passage.
2. A one-piece shuttle threader of rigid cast metal whose rearward half has an upward extension of substantially quadrantal contour transversely of the base forming a downwardly curved bridge arching across a medial longitudinal cylindrical bore and separated along its lower side from the underneath marginal portion of the base to provide a vertically narrow elongated entrance slot between top and bottom substantially parallel transversely flat edges in a lengthwise direction of the threader for a substantially greater distance than the diameter of said bore, the forward portion of said base being formed with a trough-like passage open at its top and forming a continuation of said laterally slotted cylindrical bore, said passage being bounded on one side by an upstanding yarn guiding lug located at the forward end of the base and in forward alignment with, but well spaced from, the forward end of said slot, and an elevated yarn guiding beak bounding the opposite side of said passage and having a convexly curved top converging forwardly to a vertically depending tip located in axial alignment with said bored passage.
3. A one-piece shuttle threader of rigid cast metal whose rearward half has an upward extension of substantially quadrantal contour transversely of the base forming a downwardly curved bridge arching across a medial longitudinal cylindrical bore and separated along its lower side below the middle plane of the bore from the underneath marginal portion of the base to provide an elongated entrance slot between top and bottom substantially parallel edges in a lengthwise direction of the threader for a substantially greater distance than the diameter of said bore, the forward portion of said base being formed with a trough-like passage open at its top and forming a continuation of said laterally slotted cylindrical bore, said passage being bounded on one side by an upstanding yarn guiding lug located at the forward end of the base and in forward alignment with, but well spaced from, the forward end of said slot, and an elevated yarn guiding beak bounding the opposite side of said passage and having a convexly curved top converging forwardly to a vertically depending tip located in axial alignment with said bored passage, the rear end of said bridge member being formed with a convex forwardly curving corner at its bottom to facilitate the entrance of the subtending portion of the yarn being threaded.

JAMES T. CURBOY. 40
